UNITED STATES PATENT OFFICE.

WILLIAM E. B. HASSELKUS, OF JAMAICA, NEW YORK, ASSIGNOR TO INTERNATIONAL MOTOR COMPANY, OF NEW YORK, N. Y., A CORPORATION OF DELAWARE.

SEAT.

Application filed August 17, 1926. Serial No. 129,720.

This invention relates to seats for commercial passenger carrying vehicles and particularly to seats adapted to accommodate two passengers and capable of reversal to 5 face in the opposite direction.

The object of the present invention is to provide a seat of this character wherein the back shall be disposed at the angle of greatest comfort to the occupant and which 10 is nevertheless rotatable about a vertical axis when disposed proximate adjacent seats at a distance only sufficient to afford ample room for the knees. Accordingly, provision is made for tipping the seat about its axis 15 in order that the back, which normally inclines upwardly and rearwardly, may extend in a substantially vertical direction to avoid striking the adjacent seat back as the seat is swung about. More specifically, the 20 seat is pivoted in a transverse horizontal direction upon a vertical spindle journaled in a pedestal, suitable devices being provided to prevent the tipping of the seat except when the spindle is released for rotation.

25 The invention also resides in the structure of the seat and pedestal and the associated connections which shall be practical from the standpoint of ease and economy of manufacture and convenience and durability in 30 use.

These and other objects of the invention and the means for their attainment will be more apparent from the following detailed description taken in connection with the 35 accompanying drawings, illustrating a preferred embodiment thereof, in which:

Figure 1 is a view in side elevation, partly in section, showing two of the seats according to the present invention appropriately spaced, one of which is tilted so that the back is brought nearer the vertical axis of the seat to permit it to be rotated without interfering with the seat back forwardly thereof.

40 Figure 2 is a view in front elevation, partly in section, showing the seat in position for use.

Figure 3 is a fragmentary transverse vertical sectional view showing the pedestal and swiveling connections for the seat, when actuated to permit tipping.

45 Figure 4 is a horizontal sectional view

taken in the plane indicated by the line 4—4 in Figure 3, looking in the direction of the arrows and showing details of construction 55 of the spindle and locking mechanism.

Figure 5 is a fragmentary vertical sectional view showing locking elements which normally prevent tipping and rotation of the seat in inoperative position.

60 Figure 6 is a view similar to Figure 5 but with the locking elements shown in operative position.

The seats *a*, designed to accommodate two persons side by side, are adapted to be disposed along either side, say, of a passenger carrying vehicle, one behind the other, and are spaced from one another a distance just about sufficient to conveniently accommodate the knees of the occupants. The 70 backs *a'* are inclined rearwardly and upwardly at an angle conducive to the greatest comfort of the occupants as shown clearly at the left hand side of Figure 1. The seats are designed to be turned about to face in 75 the opposite direction so that they can be used in such vehicles as rail cars, wherein the direction of travel is reversed periodically. Rotation, alone, of the seat with respect to a vertical axis is not possible since 80 the inclined back of the rotating seat would contact with the inclined back of the seat in front. The seat is therefore arranged to tip about a horizontal axis *b* so that the back may extend in a substantially vertical direction, as shown at the right in Figure 1, 85 and avoid contact with an adjacent seat back as the seat is turned.

The seat frame *a*, which supports the seat cushion *a* and the back *a'* is shown as supported yieldingly by non-metallic cushioning elements *c* from a base plate *d*. This plate is mounted by the brackets *d'*, upon a transversely extending shaft *b'* journaled in bracket *e*, carried with a rotatable spindle *e'* seated in a complementary bearing *f* carried by the pedestal *g*. When it is desired to turn the seat to face in the opposite direction the spindle *e'* is released for rotation by depressing the pedal *h* on the lever 95 *h'* fulcrumed on the pedestal at *g'*. The arm *h* of the lever is raised against the lower end of the spindle *e'* to raise it slightly and break any frictional engagement.

between the spindle and its bearing f and space the spindle flange e^2 from the bearing flange f' a sufficient distance as shown in Figures 3, 5 and 6 to raise the locking lugs

5 e^3 out of the recesses f^2 . At the same time the upright locking arm h^3 is swung outwardly bringing the roller h^4 out of the recesses e^4 f^3 in the spindle flanged e^2 and bearing flange f' , respectively. The spindle 10 is thus free to be rotated with respect to the pedestal.

The tipping of the seat is also effected by the raising of the spindle and occurs simultaneously therewith. In the longitudinal median plane of the seat there is disposed a coil spring i seated in a cylindrical housing j carried with the spindle flange f' and constantly tending to force the rear edge of the seat upwardly about 15 the shaft b as a pivot. When the seat is in operative position as shown at the left of Figure 1 the tendency to tilt is resisted by a stop diametrically opposite the spring i . This stop takes the form of a plunger k reciprocal in the spindle flange e^2 and bearing with its enlarged end k' upon the pedestal flange f' . At its top it carries adjustably a rounded bearing member k^2 which the seat engages. At the rear the cup l on the base plate d in which the upper end of the spring i seats when cooperating with the cylindrical container j for the spring forms a stop to prevent the seat tipping backward. When the spindle e' is raised the plunger k 25 remains seated on the bearing flange f' and thus the cap k^2 remains at its original elevation. The spring i at the rear, however, is raised and the forward stop being removed, the seat is free to tip forward about the shaft b .

After the seat is tipped, the spindle is rotatable without obstruction, the locking lugs e^3 and stop-plunger k riding over the surface of the bearing flange f' until the recess e^5 diametrically opposite the recess e^4 in the flange e^2 comes into register with the recess f^3 when the roller latch h^4 is forced inwardly (the foot having been taken off the pedal h) by the spring m acting 45 on the arm h^2 . The flanges are thus prevented from relative rotation and the stops e^3 are in register with the apertures f^2 and the spindle then is enabled to sink home 50 again into the housing.

55 As a measure of safety the spindle is prevented from coming entirely out of the bearing by the shoulder h^5 which overlies the spindle flange.

It will thus be seen that a reversible seat 60 has been provided which lends itself to a compact disposition when arranged in series in a vehicle, while at the same time contributing to the comfort of the occupants.

Various modifications may be made in the 65 instrumentalities availed of to afford revers-

ability without departing from the invention in its broadest aspects as delineated in the annexed claims.

What is claimed is:

1. In a reversible seat, in combination, a 70 seat frame, a pedestal, means to permit the rotation of the seat frame with respect to the vertical axis of the pedestal, said means also permitting the seat frame to be elevated, means to permit the seat frame to 75 tilt about a horizontal axis with respect to the pedestal, and means to elevate and tilt the seat frame simultaneously.

2. In a reversible seat, in combination, a 80 seat frame, a pedestal, means to permit the rotation of the seat frame with respect to the vertical axis of the pedestal, means to elevate and lower the seat frame, means to permit the seat frame to tilt about a horizontal axis with respect to the pedestal, and 85 means co-operating with the pedestal to prevent the tilting and rotating of the frame, said means being effective upon lowering of the frame.

3. In a reversible seat, in combination, a 90 seat frame, a pedestal, means to permit the rotation of the seat frame with respect to the vertical axis of the pedestal, means to elevate and lower the seat frame, means to permit the seat frame to tilt about a horizontal axis with respect to the pedestal, and 95 separate means effective upon lowering of the frame to lock simultaneously, the seat frame against rotation and tilting.

4. In a reversible seat, in combination, a 100 seat frame, a pedestal, means to permit the rotation of the seat frame with respect to the vertical axis of the pedestal, a horizontal axis about which the seat may tilt with respect to the pedestal, means to cause 105 the seat frame to tilt about the horizontal axis, means to lock the frame against rotation and manually operable means to release the frame for rotation and permit the tilting means to operate simultaneously.

5. In a reversible seat, in combination, a 110 seat frame, a pedestal, a spindle carried with the frame and journaled in the pedestal, means to prevent the spindle from rotating, means for mounting the seat frame pivotally 115 on the spindle to permit tilting, expansion means carried with the spindle and seat frame from a normal position to permit tilting of the seat frame with respect to the spindle, a stop carried with the spindle and engaging the seat frame and pedestal when the spindle and the seat frame are in the normal position to prevent tilting of the frame.

6. In a reversible seat, in combination, a 125 seat frame, a pedestal, a spindle carried with the frame and journaled in the pedestal, means to prevent the spindle from rotating, means for mounting the seat frame pivotally 130 on the spindle, expansion means carried with

- the spindle and engaging the seat frame, stop means to oppose the action of the expansion means, manually operable means to release the means to prevent the rotation of the spindle, and means operated simultaneously with the operation of the means to prevent rotation of the spindle, to prevent the stop from opposing the action of the expansion means.
- 10 7. In a reversible seat, in combination, a seat frame, a pedestal formed with a flange, a spindle journaled in the pedestal and hav-
- ing a flange, a horizontal shaft carried with the spindle, said seat frame being rotatable about the axis of the shaft, a coil spring 15 carried with the spindle flange and engaging the seat frame, a stop reciprocal in the spindle flange and seated on the pedestal flange and adapted to oppose the spring and a lever to raise the spindle with respect to 20 the pedestal and separate the flanges.

This specification signed this 10 day of August A. D. 1926.

WILLIAM E. B. HASSELKUS.
